(57) **CLAIM**

The ornamental design for a connection holder for tool attachment to construction machinery, as shown and described.

DESCRIPTION

1. Connection holder for tool attachment to construction machinery

FIG. 1.1 is a top front right perspective view of the connection holder;

FIG. 1.2 is a left side view of the connection holder;

FIG. 1.3 is a front side view of the connection holder;

FIG. 1.4 is a rear side view of the connection holder;

FIG. 1.5 is a right side view of the connection holder;

FIG. 1.6 is a top side view of the connection holder;

FIG. 1.7 is a bottom side view of the connection holder.

1 Claim, 7 Drawing Sheets
